ABSTRACT OF THE DISCLOSURE

Knitting machine needle, which has a groove formed in the shank and the beard (FIGS. 1 to 4—212) so arranged that the upper edge of at least a portion of the tip is parallel to the shaft, fitting in the groove with clearance to permit free movement of yarn to be knitted and enable positive closing without wear on the machine rail by providing a bearing surface for the machine presser bar at the upper edge of the shank where the groove is formed.

The present invention relates to a needle for knitting machines and knitting looms and more particularly to beard type needles.

The customary and usually used needles in knitting machines have a straight shaft, the lower edge of which extends from the shank end to the head of the needle in essentially a straight line. A re-entrant beard then is formed which, in the region of the head, is usually also essentially straight and then merges into a portion which is bent with respect to the axis of the needle shank. When the needle hook is closed, it fits into a groove in such a manner that the beard of the needle bears against the bottom of the receiving groove. The portion of the needle within the groove then is usually essentially parallel to the lower edge of the needle shank.

Needles, as customarily used, require precise manufacture, precise installation and precise adjustment of the operating rail of the knitting machine in which they are used in order to prevent damage to the needles. Since it is very difficult to have all needles operate in the same predetermined plane, the adjustment of the operating rail or operating bar of the machine is usually chosen in such a manner that, in order to avoid leaving one needle unclosed, the substantial majority of the needles are bent back farther than absolutely necessary, thus bending even the needle shank. The result of this overstressing is, however, that the needle tips, or the bottom of the grooves against which the beards bear, are worn off; it has been noticed, in practice, that some beard tips can be reduced in length of from 1.8 to 1 mm. The beard tip bears on the bottom of the groove with a substantial pressure. Since only the beard end of the needle contacts the bottom of the groove, a very small surface must absorb all the stress. Besides the wear on the beard tip, the upper edges of the beards also get worn in the region where the rail bears thereagainst, since the beard usually slides along the groove for a small extent, thus also rubbing against the operating rail or bar.

A further difficulty with customary needles is the resistance of the needle to transfer of the stitch. The stitch, in the knitting process, must be transferred to the closed tip, which, in machines such as warp machines, is usually done by a chopper bar or other machinery part. These chopper bars act on the stitches at the point where the stitch connects with the fabric already knitted. Since the stitch is moved by the chopper bar at the point of contact with the previously knitted fabric, the head, or formed loop of the stitch trails behind the point of contact or point of operation and transfer. This is undesired,

because if this trailing of the stitch is too much, the knitted fabric will not present a smooth appearance. In case the lag is excessive, the knitted fabric may miss a stitch and a hole may result. This is the reason why the head portion of the needle, that is, the portion between the rail or presser bar and the portion of the needle at the end thereof, may not be too short, because otherwise the angle at the upper edge of the needle, in the upper region of the edges of the groove, when the needle is closed, will be too great, and cause excessive resistance to transfer of the stitches.

It has previously been proposed to angle the tip of the needle away from the direction of the shank, in the region of the re-entrant bend. Such a needle is already an improvement. Since, when the needle is closed, the lower edge of the entire beard bears on the surface of the receiving groove, the beard is less subject to wear. Further, when the needle is closed, a better shape is imparted to the entire assembly so that the resistance of transfer of stitches to the needle is decreased.

Even the improved needles have the disadvantage that the thread or yarn can be pinched when they are used with plain, or flat warp knitting machines, since the closed needle point, to prevent wear, bears on the bottom of the groove.

It is an object of the present invention to provide a needle which can be used universally for knitting machines and knitting looms, in which excessive stressing of the needle point and thus wear is avoided, while still permitting free movement of the yarn in the groove, even when the needle is closed; and which further presents a low resistance to transfer of the stitches and is universally applicable and still provides knitted goods of uniform and excellent quality.

Briefly, in accordance with the present invention, the needle has a shank with a groove formed therein. The groove is of such dimension that it receives the re-entrant needle tip portion, or beard, with clearance to permit free movement of the yarn to be knitted. The re-entrant tip portion of the needle is formed in such a manner that the upper edge of at least a portion of the beard is parallel to the shaft, so that when the rail or operating bar presses thereagainst it completely closes the needle when it presses against the upper edge of the shank adjacent the groove. The needle shaft may be entirely straight, and a portion of the beard may be angled off so as to be parallel when closed; or the needle shank may be slightly angled at its head end to provide for the beard being parallel to the shank, when closed, and still have clearance within the groove.

When the needle is formed as a tongue, or a latch needle, the tongue is essentially aligned with the shank, that is, is in line with or slightly angled off with respect thereto, with the groove still being of sufficient size to provide clearance.

The needle, in accordance with the present invention, is so formed that the groove is deep enough in order to provide for a space therebetween and the beard. Thus, excessive pressure against the beard cannot be applied because the upper edge of the needle shank, where the groove begins, limits the extent to which the needle can be pressed into the groove. This space, between the lower edge of the beard and the groove, is large enough so that the warp in chain-stitch, lock-stitch, or loop-stitch machines can be inserted without pinching or impeding the movement of the yarn. Thus, the needle according to the present invention may be used for different kinds of machines.

Transfer of stitches to the needles according to the present invention is simple, since the stitch is transferred in an exactly straight line, which does not present any

taper opposing this transfer. The lower edge of the shaft of the needle, which may present a taper, is placed close to the point where the stitch joins to the already-made fabric, that is close to the chopper bar, so that the chopper bar itself can overcome the taper. When the stitch is cast off, there is little resistance because the remainder of the needle is straight and does not present any resistance above that of friction, which can be readily overcome, so that the lag of transfer of one portion of the yarn of the stitch with respect to another, as the length of the stitch increases, is reduced. Thus, the fabric formed is of more uniform and better quality.

The concept to improve the casting off by having the upper edge of the needle shaft, and its beard, extend in a substantially straight line, or only slightly angled, can be utilized with latching needles as well as with closed-tip needles. A latching needle, in accordance with the present invention, then will have a lower edge which is slightly angled, where the deviation from a straight line with the shank is least bothersome, because it is closest to the previously formed stitch. Thus, with latching needles, the shaft is angled off at a point starting at the throat at the lower, or under edge of the needle, while the upper edge of the tongue is in line, or substantially in line and only slightly deviating from the upper edge of the shaft.

The structure, organization and operation of the invention will now be described more specifically in the following detailed description with reference to the accompanying drawings, in which:

FIG. 1 illustrates a side view of a needle of the present invention, when open, having a beard which is angled;

FIG. 2 illustrates the needle of FIG. 1, when closed, partly in section;

FIG. 3 illustrates a needle in accordance with the present invention, in a side view, having a straight beard, when open;

FIG. 4 is a needle in accordance with FIG. 3, when closed, partially in section;

FIG. 5 is a cross-sectional view of FIG. 4 along line V—V; and

FIG. 6 is a latching needle in accordance with the present invention, in side view, with the tongue closed.

A needle shaft 210 is formed with a groove 213 (FIG. 2) and has a needle beard, or tip 212, which fits into the resting groove 213 when the needle is closed. Closing of the needle is done by the usual rail or presser bar, which is not illustrated in the drawing and forms part of the general knitting machine. It acts at a point on the needle indicated by arrow P.

The embodiment of the invention illustrated in FIGS. 1 and 2 has a shaft 210 which is straight up to the head of the needle 211. The needle tip, or beard 212 is formed with a portion 212¹ which angles off from a straight line at a bend point 212⁴, leaving another portion 212² joined with the needle head 211, to form an acute angle with the shank 210. As clearly seen in FIG. 2, when the needle is closed the tip portion 212¹ enters the receiving groove 213. The depth of groove 213 is chosen in such a manner that between the lower edge of the tip of the needle 212⁶, and the upper surface of the groove 213¹, a space 213² is left, which is large enough in order to permit the yarn or thread to move within the groove, even when the needle is closed, and to prevent pinching of the thread. The depth of closing is limited by the upper edge of the needle shank adjacent to the groove, seen at 210¹. The presser bar, or rail, which may be formed as a rod, a wheel, or other part of the machine thus cannot press the needle tip into the groove to such an extent that the tip, or the groove becomes damaged. In order to prevent damage to the thread due to misalignment of the needles, or slight imperfections in the yarn being knitted, the tip of the beard, seen at 212⁵, is bent downwardly, hook-like, towards the shank 210, as clearly seen in FIGS. 1 through 4. As particularly

appears in FIG. 2, when the needle is closed, the relationships for transfer of the stitches are particularly advantageous. The stitch does not have to overcome any increase in size, or taper, and does not have to ascend over any projecting portions of the needle, since the upper edge of the needle shaft 210¹ merges smoothly to the upper end of the needle tip 212¹.

The beard need not be angled, but may be straight. Referring now to FIGS. 3 and 4, the needle tip 211¹ when in closed position, is a straight line continuation of the upper edge 210¹ of the shank. Thus, the bent point 212⁴ (FIGS. 1 and 2) does not occur in this form of needle construction. The needle, on the contrary, is formed in such a manner that the shank 210 itself is angled off in the region of the groove 213 as seen at the portion 210². The needle beard 212, starting at head 211, that is the entire upper edge of the needle 211¹ is thus straight, so that the tip of the needle 212¹ is a straight line continuation of the front portion 212² of the beard (FIG. 3). The tip end of the beard can be bent over again as seen at 212⁵, FIG. 4.

FIGS. 3 and 4, and particularly the cross-sectional view of FIG. 5 clearly indicate that the depth of closing is again limited by the upper edge of the shaft adjacent to the groove, as at 210¹. Even when the needle is closed, there is space for a thread A in the receiving groove 213, as clearly seen at 213² in FIG. 5.

It is common to both embodiments of the present invention, that is, FIGS. 1 and 2 and FIGS. 3 to 5, respectively, that when the beard 212 is closed, the upper edge of at least a portion thereof, as at 212¹, in general is parallel to the needle shaft, that is, the portion adjacent to the groove 210¹, and that a space 213² is provided between the bottom of the receiving groove 213¹ and the lower edge 212⁶ of the needle tip (FIG. 5).

The needle shank, at its head, is slight bent, as appears at 210² (FIG. 4) and thus permits the beard to be straight. This concept can be used not only with a beard-type needle, but also with a latch-type needle. Referring now to FIG. 6, the shaft 210 is angled in the region of its throat 213⁷ as seen at 210¹²; the upper edge of the tongue 215¹ in general is an extension of the upper edge 210¹ of the shaft, and is aligned with the shaft or is angled with respect thereto only very slightly, as seen by the dash-dotted line B. The needle is formed in general in such a manner that the depth of the needle at its intermediate part 216 in general corresponds to the height of the needle head 211 (shown exaggerated in the drawing), inclusive of the tongue end 215². As has been referred to, a needle as constructed according to FIG. 6 provides for an unusually simple casting off operation, thus resulting in finer and more uniform knitted goods. The improved effect on the knitted yarn is particularly apparent in the construction according to FIG. 6, because the increase in thickness of the tongue 215, as it extends towards the needle head 211, inclusive of the tongue end 215² is usually quite appreciable with needles of known construction. This substantial and rapid increase in thickness is avoided in the construction in accordance with the present invention.

The needles themselves can be secured in the machines in which they are to be used in well-known and standard form, and the particular attachments are not shown herein.

The needles according to the present invention thus have the advantage that the depth of entry into the receiving groove is limited by the upper edge of the needle shank itself, and not by the groove surface, so that the tips of the needles are not subject to wear. Thus, since the operating parameters of the needle are determined not by the groove, but rather by the upper surface of the shank adjacent to the groove, the groove can be made sufficiently deep in order to provide space for yarn and its free movement, so that a pinching or friction against the side thereof is prevented. The longitudinal adjustment of the

needles is not nearly as critical as with needles of the prior art, since the beard is independent of bending. Thus, the needles have a long life in their machinery, further increased since the beard of the needles do not wear against the bottom of the groove. Due to the slender and gradual merging of the needle tip with the shank, the goods to be knitted can be made denser and finer, which means that the visual aspect of the goods knitted on the machinery is more pleasing. The needles themselves are entirely interchangeable in the machineries with needles of known construction, thus not requiring any re-working of existing machines.

What is claimed is:

1. Knitting machine needle, having a shank (210) ending in a tip portion (211) and a re-entrant beard (212) normally resiliently biased away from the shank of the needle (FIG. 1) in which the shank (210) is formed with a longitudinal groove (213) to receive a portion of the beard (212¹) during knitting operations, characterized in that the upper edge (210¹) of the shank and the upper edge (212¹) of said portion of the beard, when the needle is closed, are aligned; said portion of the beard (212) being dimensioned (FIG. 5) to enter the groove (213) with clearance and leave space (213²) between the bottom of the groove (213¹) and the lower edge (212⁶) of the beard portion to permit free movement of the yarn to be knitted between the beard and the bottom of the groove, the upper edges of the shank (210¹) limiting the extent of entry of the beard into the groove; the needle shank (210) is straight (FIGS. 1, 2) and said beard (212) has a second portion (212²) extending from the head of the needle (211) to an intermediate point (212⁴), said first and second portions being angled with respect to each other.
2. Needle as claimed in claim 1, wherein the tip end (212⁵) of the beard (212) is bent over in a direction towards the groove (213).
3. Knitting machine needle, having a shank (210) ending in a tip portion (211) and a re-entrant beard (212) normally resiliently biased away from the shank of the needle (FIG. 3) in which the shank (210) is formed with

a longitudinal groove (213) to receive the beard (212) during knitting operations, characterized in that

- The upper edge (210¹) of the shank and the upper edge (212¹) of the beard, when the needle is closed, are aligned; the beard (212) being dimensioned (FIG. 5) to enter the groove (213) with clearance and leave space (213²) between the bottom of the groove (213¹) and the lower edge (212⁶) of the beard to permit free movement of the yarn to be knitted between the beard and the bottom of the groove, the upper edges of the shank (210¹) limiting the extent of entry of the beard into the groove; the needle shank (210) has a head portion (210²) in the region of the groove (213), said head portion (210²) being angled (FIGS. 3, 4) with respect to the remainder of the needle shank (210) in a direction away from said beard (212), said beard (212) being substantially straight and, when the needle is closed, in line with the remainder of the needle shank.
4. Needle according to claim 3, wherein the tip end (212⁵) of the beard (212) is bent over in a direction towards the groove (213).
